UNITED STATES PATENT OFFICE.

EDWARD P. ELY, OF SOUTH WALLINGFORD, VERMONT, ASSIGNOR TO
ALEXANDER H. RITCHIE, OF NEW YORK, N. Y.

MACHINE FOR THE REDUCTION OF WOOD PULP.

SPECIFICATION forming part of Letters Patent No. 310,659, dated January 13, 1885.

Application filed November 7, 1882. (No model.)

To all whom it may concern:

Be it known that I, EDWARD P. ELY, a citizen of the United States, residing at South Wallingford, Vermont, have invented certain new and useful Improvements in Machines for the Reduction of Wood Pulp, of which the following is a specification.

My invention relates to improvements in a machine for reducing wood pulp, described 10 and claimed in my previous application, Serial No. 109,898, filed October 24, 1883; and it consists in enlarging the lower terminus of the power-shaft of the machine into a cap concave on its under side, and adapted to fit over and 15 turn on a convex step, the said cap and step being situated in a water-tank, and constructed, preferably, of hard wood—such as oak, locust, &c.—whereby the friction caused by the main shaft in its lower bearings will be distributed 20 over a larger surface, decrease the wear and tear, and, by means of the surrounding water-tank, prevent the rubbing contacts from becoming heated. In the present device, also, the arms or spokes of the machine are re-enforced by means of braces or brackets extending 25 from beneath the emery ring or wheel to suitable places on the main shaft, by this means centralizing the pressure upon said shaft and its lower bearings, as will be hereinafter 30 more fully described.

The above-mentioned step is provided with a set-screw, and is adjustable vertically.

The accompanying drawing represents a side elevation, partly in section, of my improved machine.

A is the power-shaft or main spindle, receiving motion from any suitable source, and provided with a hub, B, having arms or spokes C extending from it. These arms C are provided 40 with braces C', keyed or otherwise rigidly attached to the shaft A at A'. The outer ends of the spokes C protrude into the circular trough or hollow frame H, which latter is provided for the reception of the wood pulp when 45 ground. Resting upon and attached to the spokes C is a ring, D, adapted to turn with the other rotating parts. D' is the emery filling in the upper surface of the ring. This ring may be continuous, or it may be formed in 50 sections, whichever in practice may be found most desirable. The circular pulp-trough H

is formed in two portions—an upper and a lower—and is joined together at h. By this arrangement the upper half may be removed, permitting the emery-ring D to be easily taken 55 out and renewed whenever it is desired. The hoppers, the automatic feeding arrangement, the means and method for supplying water to the emery-ring, and the means for sifting the wood pulp are all the same or substantially 60 the same as those employed in my application above referred to. The lower portion of the main shaft A is provided with a cap, v, concave in its under side. This cap rests and travels upon a step, w, which is made convex 65 upon its upper surface. Surrounding these parts, which are made, preferably, of hard wood, is a tank, x, adapted to hold water, in order to keep the rubbing portions of v and w constantly cool and smooth. The step w is set in the 70 bridge-tree y, and is provided with a set-screw, y', for adjusting the bearings and taking up the wear caused by the rotating parts. Adjustable bearings z are also provided at both sides, or all around the main shaft, taking up any horizontal shifting.

Having thus described my invention, what I claim as new therein, and desire to secure by Letters Patent, is—

1. In a wood-pulp machine, the vertical 80 power-shaft having means for rotating an emery-ring, and provided with a cap adapted to rest and travel on a step, the said cap and step being respectively concave and convex, as and for the purposes set forth.

2. In a wood-pulp machine, the combination 85 of the main power-shaft, the cap having the concave lower surface, the step having the convex upper surface, and the surrounding water-tank, all arranged substantially as and 90 for the purposes set forth.

3. In a wood-pulp machine, the combination, 95 with vertical power-shaft and the concave cap, of the step adapted to form a bearing-surface for the above, and provided with means of adjustment, substantially as described.

4. In a wood-pulp machine, the combination 100 of the vertical power shaft or spindle having arms or spokes adapted to turn an emery-ring, and the braces placed directly under said emery-ring and extending downwardly and attached to the power-shaft, for strengthening

the arms and supporting the arms and ring, as set forth.

5. In a wood-pulp machine, the vertical power-shaft having a loose bearing at bottom, substantially as described, in combination with an adjustable bearing surrounding said shaft, whereby it is confined to its plane of rotation, as explained.

6. In a wood-pulp machine, the vertical power-shaft having means for rotating an emery-ring, and provided at its lower end with a bearing-surface of hard wood, in combination with a bearing-step, formed also of wood, and

a water-tank surrounding the same, as and for the purpose set forth.

7. The combination of a vertical shaft, a suitable step at bottom, upon which it rests and revolves, a water-tank surrounding the same, and means for maintaining them in axial alignment, substantially in the manner and for the purpose set forth.

EDWARD P. ELY.
